DESIGN.

W. C. HIGGINS.

HEATING STOVE.

No. 15,613.

Patented Dec. 16, 1884.

UNITED STATES PATENT OFFICE.

WERTER C. HIGGINS, OF NORWICH, CONNECTICUT.

DESIGN FOR A HEATING-STOVE.

SPECIFICATION forming part of Design No. 15,613, dated December 16, 1884.

Application filed October 25, 1884. Term of patent 7 years.

To all whom it may concern:

Be it known that I, WERTER C. HIGGINS, of Norwich, in the county of New London and State of Connecticut, have invented and produced a new and original Design for Stoves, of which the following is a specification, reference being had to the accompanying drawing, forming a part of this specification.

The figure is a perspective view of my newly-
designed stove.

A designates the base of the stove, which is circular in form, and is ornamented with the design a. At its lower edge the base is also ornamented with the embossed design a'. The hearth-cover B is ornamented with the design b. The legs C are ornamented with the designs c c'. The door is set in a panel, D, ornamented with the designs d d'. D' designates the cylindrical body of the stove. The crown E of the stove is of the form shown, and is ornamented with the designs e, e', e'', and e', and the urn F is ornamented with the designs f f' f'' f'.

I have deemed it necessary to refer to the several ornamental configurations by letter only, inasmuch as the ornaments are clearly shown in the drawing, and no clearer conception of their character can be conveyed than that obtained by visual inspection, aided by the letters of reference.

The form of the stove, and also of the ornaments, as shown, is to be specifically adhered to.

Having thus described my new and original design, I claim—

The design for stoves herein shown and described, consisting of the base A, having the ornamental designs a a', the hearth-cover B, having the design b, the legs C, having the designs c c', the door-panel D, having the designs d d', the crown E, having the ornamental designs e e' e'' e', and the urn F, having the designs f f' f'' f', as shown and described.

WERTER C. HIGGINS.
